Primary Examiner — Mimosa De

(57) **CLAIM**

The ornamental design for an unfoldable cabinet, as shown and described.

DESCRIPTION

FIG. 1 is a perspective view of an unfoldable cabinet in the closed state, showing my new design;

FIG. 2 is a perspective view of an unfoldable cabinet in the open state;

FIG. 3 is a front elevational view thereof;

FIG. 4 is a side elevational view thereof; and,

FIG. 5 is a top plan view thereof.

The claimed unfoldable cabinet is used to store a variety of content, including without limitation, general merchandise, jewelry, watches, and cosmetics, and its drawers are capable to unfold almost flat and fold back into erected position.
